[57] CLAIM

The ornamental design for an aerial toy, as shown and described.

DESCRIPTION

FIG. 1 is a top plan view of an aerial toy showing my new design, the side opposite being substantially a mirror image;

FIG. 2 is a cross-sectional view thereof taken along the horizontal reference lines in FIG. 1;

FIG. 3 is a cross-sectional view thereof taken along the vertical reference lines in FIG. 1;

FIG. 4 is a top plan view of a modified embodiment of the design shown in FIGS. 1 through 3;

FIG. 5 is a cross-sectional view thereof taken along the horizontal reference line in FIG. 4; and

FIG. 6 is a cross-sectional view thereof taken along the vertical reference lines in FIG. 4.

FIG. 1

FIG. 2

FIG. 3
